CLAIM

The ornamental design for a smartwatch as shown and described.

DESCRIPTION

1. Smartwatch
2. Smartwatch
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : partially enlarged view of detail 9 in FIG. 1.1
- 2.1 : Perspective
- 2.2 : Perspective
- 2.3 : Front
- 2.4 : Back
- 2.5 : Left
- 2.6 : Right
- 2.7 : Top
- 2.8 : Bottom

2.9 : partially enlarged view of detail 18 in FIG. 2.1

The broken (dashed) lines show portions of the smartwatch that form no part of the claimed design; Dot dash lines and label 9, 18 shown in the reproductions 1.1 and 2.1 indicate the position of the enlarged view and form no part of the claimed design.
